UNITED STATES PATENT OFFICE.

HERBERT W. COOPER, OF MOLINE, ILLINOIS.

DESIGN FOR A NECK-YOKE BAND.

SPECIFICATION forming part of Design No. 24,950, dated December 3, 1895.

Application filed June 4, 1895. Serial No. 551,687. Term of patent 31 years.

To all whom it may concern:

Be it known that I, HERBERT W. COOPER, a citizen of the United States, residing at Moline, Illinois, have invented and produced a new and original Design for Neck-Yoke Bands, of which the following is a specification, reference being had to the accompanying drawing.

The leading feature of my design consists in a parti-cylindrical body having straight parallel flanges or extensions and crimped beads on the ends of the body.

A represents the body, which is hollow and

parti-cylindrical or tubular in form with straight extensions or flanges B, provided with the apertures b. On the ends of the body are curved beads a, which bound the ends of the parti-cylindrical portion and terminate at the junction of the flanges with said curved body.

I claim—

The design for a neck yoke band substantially as herein shown and described.

HERBERT W. COOPER.
